UNITED STATES PATENT OFFICE.

GUSTAV FUCHS, OF CHICAGO, ILLINOIS.

DESIGN FOR A CIGAR-CLIPPER CASE.

SPECIFICATION forming part of Design No. 34,366, dated April 16, 1901.

Application filed February 9, 1901. Serial No. 46,752. Term of patent 7 years.

To all whom it may concern:

Be it known that I, GUSTAV FUCHS, a citizen of the United States, residing at Chicago, Cook county, State of Illinois, have invented and produced a certain new and original Design for a Cigar-Clipper Case; and I do declare that the following is a description of the invention sufficiently clear, full, and exact to enable others skilled in the art to which it appertains to make and use the same, attention being called to the accompanying drawing, which forms also a part of this specification.

This invention relates to casings or housings for an automatic cigar-clipper; and the object is to improve and enhance the appearance of such a casing by certain novel and pleasing effects obtained by the provision of certain ornaments and parts and their arrangement, shape, and outline, as well as appearance of the outer surfaces of such casing, all as hereinafter described, and illustrated in the accompanying drawing, which shows in perspective view such a casing embodied with the design contemplated by my invention.

The design consists of a box-shaped structure or housing which constitutes the case of an automatic cigar-clipper.

The style of the casing is in imitation of an old-fashioned oak chest or antique treasure-box, the inclosing sides having the appearance of oak wood and the corners being bound and covered with ornamental iron trimmings of the shape and outline as shown and secured by rivets to the sides of the casing. Straps or tongues of similar shape and outline extend also from these corner-trimmings inwardly and partly over the sides of the casing. There is also a hasp or similar ornament secured to the lid of the box and a staple to the front to receive an old-fashioned padlock to complete the intended imitation of the particular style of chest.

About in the middle of the top there is a circular opening, being the opening of the cigar-clipper case.

Having described my invention, I claim as new—

The design for a cigar-clipper case, substantially as shown and described.

In testimony whereof I hereunto set my hand in the presence of two witnesses.

GUSTAV FUCHS.
